CLAIM

The ornamental design for a process cartridge for image forming apparatus, as shown and described.

DESCRIPTION

FIG. 1 : Front

FIG. 2 : Back

FIG. 3 : Top

FIG. 4 : Bottom

FIG. 5 : Left

FIG. 6 : Right

FIG. 7 : Perspective

FIG. 8 : Perspective

FIG. 9 : Enlarged view of FIG. 5; and,

FIG. 10 : Enlarged view of FIG. 6.

1 Claim, 10 Drawing Sheets(56)
